Patented Oct. 3, 1922.

4 SHEETS—SHEET 1.

The drawing consists of two parts: a top view labeled 'Fig. 1' and a cross-sectional view labeled 'Fig. 2'.

Fig. 1 (Top View): Shows a rectangular vessel structure. The top surface features a central rectangular area with a grid of small square holes. This area is labeled '15c'. Above this grid, there is a circular area labeled '15a'. The top surface is marked with several labels: '15b' on the left, '15d' on the right, '15e' at the top left, '15f' at the top right, '15g' at the bottom left, and '15h' at the bottom right. The vessel is supported by four legs, each labeled '21'. The legs are connected to a horizontal beam labeled '22'. The entire vessel is surrounded by a hatched border.

Fig. 2 (Cross-Section): Shows a cross-section of the vessel's base. It features four vertical legs labeled '21' and a horizontal beam labeled '22'. The beam '22' is supported by a central vertical structure labeled '23'. The base is labeled '24'. The cross-section also shows internal components labeled '25a' and '25b'.

Labels: The labels include '15a', '15b', '15c', '15d', '15e', '15f', '15g', '15h', '21', '22', '23', '24', '25a', '25b', and '26'.

UNITED STATES PATENT OFFICE.

WILLIAM E. ELLIOTT, OF STRUTHERS, OHIO.

GAS-PRODUCING APPARATUS.

Application filed January 17, 1920. Serial No. 352,193.

To all whom it may concern:

Be it known that I, WILLIAM E. ELLIOTT, a citizen of the United States, and a resident of Struthers, in the county of Mahoning and State of Ohio, have invented certain new and useful Improvements in Gas-Producing Apparatus, of which the following is a specification.

My invention relates to an apparatus for producing combination water and coal gas, and more particularly to an apparatus for treating bituminous coal to produce water and coal gas.

The purpose of my invention is the provision of a gas producer of the type above specified which combines in a single apparatus gas producing, carbureting, and heating means to eliminate the separate apparatus generally required for each of these means, with their attendant disadvantages; this combining of the several apparatus being accomplished in such manner as to greatly enrich the gases produced and to materially increase the gas producing capacity of the apparatus over similar apparatus heretofore proposed.

I will describe one form of gas producing apparatus embodying my invention and will then point out the novel features there-
of in claims.

In the accompanying drawings:

Figure 1 is a view showing in horizontal longitudinal section one form of gas producing apparatus embodying my invention.

Figure 2 is a vertical transverse sectional view taken on the line 2-2 of Figure 1.

Figure 3 is a view similar to Figure 2 taken on the line 3-3 of Figure 1.

Figure 4 is a vertical longitudinal sectional view of the apparatus shown in the preceding views.

Figure 5 is an enlarged detail view showing in perspective the retort shown in the preceding views.

Similar reference characters refer to similar parts in each of the several views.

Referring specifically to the drawings, B designates a retort bench preferably formed of brick and of the contour shown in Figure 1. This bench B is preferably covered by an asbestos casing J, and as shown in Figure 4 such bench is divided longitudinally by means of partitions P and P' into three separate and distinct compartments

designated C', C² and C³. At a point above the compartments C, the bench B is formed with a slightly arched wall W which is coextensive in length with the bench to provide a compartment K. Arranged centrally within the compartment K and supported on the wall W is a brick retort R of the shape shown in Figure 5, wherein it will be seen that it comprises a semi-circular top portion 15 and a slightly arched bottom portion 16. At regular spaced intervals throughout the length of the retort R, the sides of the top portion 15 are formed at corresponding points with inlet ports designated 15^a, 15^b and 15^c, respectively, one pair for each of the compartments C. These ports effect a communication between the compartment K and the interior of the retort R at intervals throughout the length of the latter. Each port 15^a, etc., is controlled by a valve V which is formed of brick and manipulated to open or close the port through a rod D which extends through a suitable opening formed in the top wall of the bench so that it can be manually operated from the top of the apparatus. To effect a proper seating of the valve V within the ports, the retort R is recessed at points directly below the ports as at 17 in Figure 5.

As shown in Figure 4, an opening 18^a is formed at the forward end of the retort R which communicates with a waste heat pipe H that extends exteriorly of the bench to a remote point where it communicates with a boiler (not shown). The rear end of the retort R is open to allow of the free passage of the gases into the retort whence they exit at the forward end into a pipe H' which communicates with any standard form of gas purifying system in which a suitable fan Q is included for creating a suction within such pipe so as to withdraw the gases from the retort R.

At any point in the rear of the medial portion of the rotort R a pipe H² communicates with the top portion 15 for the purpose of introducing tar into the retort. The tar is preferably forced into the retort in the form of a spray by means of steam which is supplied to the tar pipe H² through a pipe H³, the latter being connected to the boiler previously mentioned so that this steam is generated by the waste

heat from the coal, thus eliminating the provision of a separate heating means.

As shown in Figure 2, each compartment C is provided with a grate G which divides the same into a fire box F and an ash pit A. Coal in predetermined quantities is supplied to each fire box F through a hopper 18 arranged at the top of the bench and communicating with a pipe 19 which extends 10 downwardly through the top wall of the bench and the wall W, its lower end being curved so as to deliver the coal centrally of the fire box. Each pipe 19 is formed with a screen opening 19^a through which 15 the gases from the coal in the fire box are adapted to pass into the compartment K. As shown in Figures 2 and 4, the side walls of the compartments C are formed with door controlled openings 20 through which 20 access may be had to the fire box F and ash pits A for inspection and cleaning purposes.

As shown in Figures 1 and 3, E', E² and E³ designate pipes for supplying blasts of air to the compartments C', C² and C³, respectively. Each pipe is provided with two branches 21 and 22, the former of which communicates with the corresponding ash pit A and may be termed the primary air supply, while the latter communicates with 30 a corresponding fire box F and may be termed a secondary air supply pipe. The passage of air through each pipe is controlled by valves 21^a and 22^a, respectively, these valves being of the standard construction 35 and arranged preferably in the horizontal portion of the pipes. As shown in Figure 3, a pipe E⁴ controlled by a valve e communicates with the ash pit A of each compartment for the purpose of supplying steam 40 to and beneath the coal in the fire box for a purpose which will be described hereinafter.

As illustrated to advantage in Figures 1 and 5, the retort R is provided with a plurality of rectangular recesses 24 which are arranged in staggered relation to each other for the purpose of receiving and supporting on end a plurality of baffled members M. These members M are formed of brick and because of the staggered manner in which 50 they are arranged, tortuous passages are formed within the retort which tend to retard the passage of gas therethrough as will be more fully described hereinafter.

The operation of the apparatus is as follows: After the coal has been introduced into the compartments C through the pipes 19 and ignited, blasts of air are admitted beneath the ash pits A by opening the valves 21^a which obviously creates a draft that 60 rapidly increases the intensity of the heat. As soon as the heat has reached the gas generating point the valves 21^a are closed and a new supply of coal is admitted through the pipes 19, and the valves e are 65 opened admitting jets of steam beneath the

burning coal. These jets of steam soften the ashes; the steam combining with the incandescent coal or coke and forming water gas. The green coal, reposing on top of the incandescent coal is partly decomposed due to coming in contact with the hot coal below thus forming coal gas. The steam drives the mixture of the two gases upwardly of the fire box and into the compartment K through the pipes 19 and the openings 75 19^a. As previously stated, a suction is created within the pipe H' so as to generate a draft in the direction of the forward end of the retort R. Under the action of this suction, the gases which enter the compartment 80 K travel rearwardly and into the rear end of the retort R as indicated by the arrows in Figure 1, it being understood that the ports 15^a are closed during this operation. Upon entering the retort R the gases impinge 85 against the faces of the baffle members M and are projected off at opposite sides so that they impinge upon the baffle members next in advance, as indicated by the arrows in Figure 1. This action of the gases is continued 90 throughout the entire length of the retort, and as a result the passage of the gases therethrough is retarded, and at the same time the globules comprised in the gases are broken up to effect a more thorough 95 fixing of the gas. The purpose of retarding the passage of the gases through the retort is to retain the same therein for a time sufficient to allow all the by-products to be converted into permanent gas. Should 100 any carbon accumulate upon the surfaces of the baffle members M because of the cooling of the gases, during transit from the boxes to the retort, such carbon can be effectively and quickly consumed by admitting short 105 blasts of air to the fire box adjacent its upper end, this air passing into the compartment K and finally into the retort R through the several ports 15^a, etc., by moving the valves V to open such ports. This 110 admission of air at different points along the length of the retort R effectively consumes the carbon in the retort, at the same time bringing the temperature in the retort back to the proper degree for proper carburation.

Any tar which exists from the producer as a result of incomplete conversion is returned to the retort R through the pipe H², after the secondary air has been admitted through the ports 15^a, etc., it being understood that because of the intense heat generated within the retort the tar as it enters the retort is immediately turned into a fixed gas and finally passes outwardly through 115 the pipe H'.

Although I have herein shown and described only one form of gas producing apparatus embodying my invention, it is to be understood that various changes and modifi- 120 125 130

cations may be made herein without departing from the spirit of the invention and the spirit and scope of the appended claims.

What I claim is:

5. 1. A gas producing apparatus comprising, a plurality of coal burning compartments, a retort above said compartments lengthwise through which gas passes, means for conducting the gases from the compartments to one end of said retort, valve controlled means for introducing air interiorly of the retort at points intermediate its ends, a suction pipe communicating with said retort, and means within the retort for retarding the passage of gas therethrough. 70
- 10 2. A gas producing apparatus comprising, a plurality of coal burning compartments, a compartment above the first compartments and communicating with all of the same, a retort arranged within the second compartment and having one end in communication with said compartment, ports formed at intervals throughout the length of said retort, means for controlling said ports, baffle members arranged in staggered relation within said retort, and a suction pipe communicating with the opposite end of said retort. 80
- 15 3. A gas producing apparatus comprising, a plurality of coal burning compartments, a second compartment communicating with all of said compartments and arranged above the same, a retort within the second compartment and overlying all of the first compartments, said retort having one open end communicating with said compartment and ports formed intermediate the ends thereof to effect communication between the second compartment and the interior of the retort, valves for controlling said ports, a suction pipe at that end of the retort which is not in communication with the second compartment for creating a draft through the retort in the direction of the pipe, and means within the retort for retarding the passage of fluids therethrough. 90
- 20 4. A gas producing apparatus comprising, a plurality of gas burning compartments, a retort overlying all of said compartments and having one end thereof in communication therewith, a suction pipe in communication with the opposite end of said retort for creating a draft through the retort to cause the gases from the first compartments to pass lengthwise through said retort, valve controlled means for introducing gases from the first compartments into the retort at points intermediate its ends, and means for retarding the passage of gas through said retort. 100
- 25 5. A gas producing apparatus comprising, a plurality of coal burning compartments, a retort overlying all of the compartments and having one end thereof communicating therewith, a suction pipe for creating a draft through said retort to cause the gases to enter the same at said end, means for introducing tar into said retort, and means for retarding the passage of gases through said retort. 105
- 30 6. A gas producing apparatus comprising a bench divided into a plurality of compartments, means for supplying coal to said compartments, a grate in each of said compartments arranged to provide a fire box 75 and an ash pit, means for introducing a blast of air below said grate, means for introducing steam below said grates, means for introducing blasts of air into said fire boxes above the grates, a retort overlying said compartments and having one end thereof in communication with all of the same, valved ports formed in the retort intermediate its end, a suction pipe communicating with the opposite end of said retort 85 for creating a suction through the retort in the direction of the pipe, and means within said retort for retarding the passage of fluids therethrough. 95
- 35 7. A gas producing apparatus comprising, a bench divided into a plurality of compartments, means for supplying coal to the compartments, a grate in each of said compartments arranged to divide the same into a fire box and an ash pit, means for intensifying the heat generated by the coal in each compartment to a gas generating point, means for softening the ashes within each of the compartments, means for supplying blasts of air to each compartment 100 above the grates, a retort overlying all of said compartments and communicating at one end thereof with the same, valved ports in the retort between its ends, a suction pipe communicating with the opposite end of said retort for creating a suction through the same, to draw the gases from the compartments into the retort, and baffle members in the retort for fixing the gases as they traverse the retort. 110
- 40 8. A gas producing apparatus comprising, a bench divided into a plurality of compartments, each compartment comprising a fire box and an ash pit, means for supplying coal to each compartment, means to introduce steam for softening the ashes within each compartment in a manner to liberate and drive the gases from the coal within the fire boxes, a retort overlying all of the fire boxes, means for mixing and 115 delivering the gases from the fire boxes to one end of the retort, suction means to draw the mixed gases longitudinally through the retort, and gas retarding means within the retort to bring about fixing of the gases 120 during transit. 125
- 45 9. A gas producing apparatus comprising, a bench divided into a plurality of compartments, each compartment comprising a fire box and an ash pit, means for supplying 130

air and steam to each compartment, a retort overlying all of said fire boxes and communicating at one end thereof with the same, a suction pipe communicating with the opposite end of said retort, ports formed in said retort intermediate its ends in a manner to effect communication between said compartments and said retort, and manually operable means for controlling said ports.

10. A retort for gas producing apparatus comprising, an elongated hollow member having a flat bottom wall and curved side walls, the opposite ends of said member being open, and valved ports formed in the side walls thereof at intervals throughout the length of the walls.

11. A retort for gas producing apparatus comprising, a hollow member having a flat bottom and a curved top, ports formed at intervals in said top, and valves controlling said ports.

12. A retort for gas producing apparatus comprising, a hollow member having a flat bottom and a curved top, ports formed at intervals in said top, said bottom being formed with staggered recesses, and baffle members supported in said recesses.

13. A gas producing apparatus comprising, a bench divided into a plurality of

separate and distinct coal burning compartments, a second compartment overlying the first compartments and communicating with the same, a retort within the second compartment and communicating at one of its ends with the same, and means for introducing coal to said compartments, each of said means comprising, a pipe extending downwardly through the upper wall of said bench and through the second compartment, the lower end of said pipe being curved in the direction of the center of the corresponding compartment.

14. A gas producing apparatus comprising, a bench divided into a plurality of coal burning compartments, a wall above said compartments and arranged to provide a second compartment above the first compartments, pipes extending through the second compartment and said wall and into the first compartments, said pipes being provided with openings between their ends to effect communication between the first compartments and the second compartment, and a retort within the said compartments and communicating at one of its ends with the latter.

WILLIAM E. ELLIOTT.
